(57) **CLAIM**

The ornamental design for a docking station for a hand held X-ray fluorescence (XRF) instrument, as shown and described.

DESCRIPTION

FIG. 1 is an isometric view of the presently disclosed docking station, including the hand held analyzer and an extra battery.

FIG. 2 is a right side view of the presently disclosed docking station, including the hand held analyzer and an extra battery.

FIG. 3 is a left side view of the presently disclosed docking station, including the hand held analyzer and an extra battery.

FIG. 4 is a front view of the presently disclosed docking station, including the hand held analyzer and an extra battery.

FIG. 5 is a back view of the presently disclosed docking station, including the hand held analyzer and an extra battery.

FIG. 6 is a top view of the presently disclosed docking station, including the hand held analyzer and an extra battery; and,

FIG. 7 is a bottom view of the presently disclosed docking station, including the hand held analyzer and an extra battery.
